(57) **CLAIM**

The ornamental design for a device for protection against x-rays, as shown and described.

DESCRIPTION

FIG. 1 is a perspective view of a device for protection against x-rays according to my design;

FIG. 2 is a front view thereof thereof;

FIG. 3 is a rear view thereof;

FIG. 4 is a top view thereof thereof;

FIG. 5 is a bottom view thereof;

FIG. 6 is a right side view thereof; and,

FIG. 7 is a left side view thereof.

The broken lines illustrate environmental structure and are for illustrative purposes only. The broken lines form no part of the claimed design.

1 Claim, 5 Drawing Sheets
